Assignee website, Trinity EcoStorage Bamboo Trash Bag Dispenser, Jul. 10, 2025, <https://trinityii.com/products/trinity-ecostorage%20AE-bamboo-trash-bag-dispenser-set-of-2> (Year: 2025).*Primary Examiner — Nathan M Johnston(74) *Attorney, Agent, or Firm* — INNOVATION CAPITAL LAW GROUP, LLP; Vic Lin(57) **CLAIM**

The ornamental design for a trash bag holder as shown and described.

DESCRIPTION

FIG. 1 is a perspective exploded view of a trash bag holder, with a side door detached, showing my new design;
FIG. 2 is a front elevation view thereof;
FIG. 3 is a rear elevation view thereof;
FIG. 4 is a left side elevation view thereof;
FIG. 5 is a right side elevation view thereof; and,
FIG. 6 is a top plan view thereof.
The bottom of the trash bag holder is flat and unornamented.
